Attorneys

UNITED STATES PATENT OFFICE

CLIFFORD A. SCHACHT, OF HUNTINGTON, INDIANA

SLIDING CASTER

Application filed May 8, 1931. Serial No. 536,026.

This invention is a novel improvement in sliding casters for use on beds, chairs and other articles of furniture; and the principal object of the invention is to provide a resilient sliding caster which will be economical to manufacture, having a cushion body of resilient rubber, with a caster pintle mounted therein having a universal rocking movement with respect to the caster body, whereby when the caster is applied to a chair leg or the like, the chair can be tilted but the universal movement of the pintle will allow the base of the body to remain flat on the surface of the floor at all angles, thereby preventing sharp corners or edges of the chair or other furniture legs from digging in, and from making ugly scars and spots on the floor; hence my novel casters will give longer life to floors and floor coverings. My sliding casters may be applied to the furniture by merely removing the ordinary caster and replacing same with my caster in the same socket.

I will explain the invention with reference to the accompanying drawing which illustrates several practical embodiments thereof to enable others to adopt and use the same; and will summarize in the claims the novel features of construction, and novel combinations of parts, for which protection is desired.

In said drawings:

Fig. 1 is a perspective view of a chair equipped with my novel casters, showing the chair tilted backwardly and the casters on the rear legs seated squarely on the floor surface.

Fig. 2 is an enlarged vertical section through one form of caster and pintle.

Fig. 3 is a perspective view illustrating the universal rocking movement permitted the pintle.

Fig. 4 is an enlarged vertical section through a modified form of caster.

Fig. 5 is an enlarged vertical section through a further modified form of caster.

Figs. 6, 7 and 8 are views showing the casters applied by riveting or bolting to conventional legs of metallic furniture.

As shown in Figs. 1, 2 and 3 my novel sliding caster preferably consists of a substantially

conical or semi-conical body 1 of soft resilient rubber or other yieldable material, having an axially disposed recess 1a in its upper end of greater diameter than the pintle 2, said recess 1a extending downwardly about half of the height of the body 1.

Below the recess 1a is a reduced cylindrical and axially disposed bore 1b adapted to snugly receive the lower end of the pintle 2 adjacent its ball head 2a in order to maintain the pintle 2 normally in vertical position while yieldably permitting universal rocking movement thereof, as in Fig. 3; said portion 1b also maintaining the pintle 2 properly centered in the resilient body 1 with its head 2a in the seat 3a, hereinafter described.

Below the reduced bore 1b is a recess 1c adapted to snugly receive the head 2a of pintle 2, the material of the rubber body below the recess 1c being cut away as at 1d to expose the head 2a when positioned in the recess 1c, whereby the head 2a of the pintle may engage the raised socket portion 3a of the metallic cup-like shell 3 which embraces the lower portion of the rubber body 1 as shown in Fig. 2. The recesses or bores 1a, 1b, 1c and 1d are all preferably preformed by molding in the rubber body and the pintle 2 is inserted therein from the underside through recess 1d by forcing the pintle therethrough until the head 2a seats in its recess 1c. Preferably a shoulder 1e is also molded in the body separating the bore 1b and recess 1c, said shoulder being adapted to engage the flattened upper end 2b of head 2a of the pintle in order to prevent the head 2a from being pulled upwardly out of recess 1c and hence entirely through the body 1.

Around the lower portion of the rubber body 1 is a metallic cup-shaped shell 3 adapted to fit tightly around the lower end of the body, the shell being provided at its center with a raised socket seat 3a extending upwardly into the recess 1d, so that when the pintle 2 is forced into position in the body as shown in Fig. 2 the head 2a will rest in the metallic socket 3a, whereby the pintle may have a universal rocking movement with respect to the body 1, as shown in Fig. 3.

The rubber body 1 is preferably larger than

the inside of the sliding metallic shell 3. While there are a number of ways of inserting the rubber in the shell, I preferably insert the rubber in the partially formed shell 3 and then by means of a press contract the upper end of the shell around the body to lock the rubber securely therein.

5 The caster pintle is preferably made with an offset collar or shoulder 2c disposed within 10 the recess portion 1a of the rubber body 1, said collar or shoulder limiting the downward movement of the plug or plate P mounted on the pintle which carries the furniture leg L, said downward movement under weight of 15 the furniture compressing the flexible upper rim of the rubber body 1 to form a yieldable cushion. The collar or shoulder 2c however on the pintle may be omitted if desired. Any 20 type of plate or plug may be used in connection with the pintle.

By the above construction the pintle 2 is 25 permitted a universal rocking motion with respect to the body 1 and shell 3, whereby when the chair or other article of furniture is tilted 30 the sliding caster will remain seated squarely on the surface of the floor while the pintle 2 may readily assume the angularity of the furniture leg, thereby preventing injury to the floor.

30 The caster shown in Fig. 4 is substantially the same as that shown in Fig. 2, except that the rubber body 11 is of somewhat less height; also the recess 11a in the upper end of the body 11 is also of less depth. The pintle 12 is somewhat modified, same being provided with the collar 12c upon which is seated a perforated plate Q, adapted to be screwed against the lower end of the furniture leg L; and the shank of pintle 12 is loosely riveted 40 as at 12e over the upper face of plate Q.

45 In Fig. 5 a slightly different modification is illustrated, in which the ball head 22a of the pintle is entirely embedded in the rubber body 21 and does not extend downward- 50 ly to engage a seat (such as 3a in Fig. 2) in the metallic shell 23. In this modification the spherical recess 21f for the ball head would be formed by molding in the rubber body so that the pintle head 22a could be 55 forcibly inserted therein from the upper end of the body. The metallic shell 23 has no offset seat, such as 3a; and the rubber body 21 has no recess corresponding with 1d in Fig. 2 for exposing the head 22a 60 through the lower end of the body 21. The shank 22 is provided with the collar 22c, but no flattened surface on the head 22a (such as 2b in Fig. 2) is provided for in this modification. Such flattened surface would interfere with the ready removal of the pintle from the recess 21f. Shank 22 may be provided with any type of plate or plug, but as shown, the plug P¹ is of the expandable type, same being formed of a strip of metal bent 65 into substantially rectangular form and

perforated at its top and bottom for the passage of the pintle 22. A washer P² is inserted between the plug P¹ and collar 22c, and under weight of the furniture the washer may be depressed sufficiently to seat upon the 70 collar, the soft upper end of the body 21 forming a resilient cushion for the weight of the furniture.

In Figs. 6 and 7 the pintles are shown connected with conventional metallic furniture legs P³, the upper end of the pintle 32 being riveted as at 32f in Fig. 6 to the furniture leg; and pintle 42 is, bolted to the leg P³ as at 42g in Fig. 7. In Fig. 8 the upper end of the pintle 52 is bolted as at 52h to a cap P⁴ 80 which is secured to the lower end of the metallic leg P⁵ of the furniture. Washers P² are inserted between the legs P³ and cap P⁴ and the body 1 of the casters. The method of attaching the pintle to the leg may be 85 varied as desired.

I do not limit my invention to the exact forms shown in the drawing, for obviously changes may be made therein within the scope of the claims.

90 I claim:

1. A sliding caster, comprising a resilient body having a bore therein wider at its top than at its lower end; a pintle having a head at its lower end centered in the bore and 95 adapted to pivot universally of the body; and a shell mounted on the body.

2. In a sliding caster as set forth in claim 1; said pintle having a collar thereon disposed within the enlarged upper end of the 100 bore for limiting the compression of the body due to weight supported by the caster.

3. A sliding caster, comprising a resilient body having a bore therein wider at its top than at its lower end; a pintle having a ball 105 head on its lower end centered in the bore, and adapted to pivot universally of the body; and a shell mounted on the body having a raised socket portion opposite the lower end of the bore forming a seat for the ball 110 head.

4. In a sliding caster as set forth in claim 3; said pintle having a collar thereon disposed within the enlarged upper end of the 115 bore for limiting the compression of the body due to weight supported by the caster.

5. A sliding caster, comprising a resilient body wider at its base than at its top and having an axial bore therein wider at its top than at its lower end; a pintle having a ball 120 head centered in the lower end of the bore and adapted for universal rocking motion with respect to the body; and a shell on the body having an axially disposed raised socket portion opposite the lower end of the bore forming a seat for the lower end of the pintle.

6. In a sliding caster as set forth in claim 5; said pintle having a shoulder thereon disposed within the enlarged upper end of the 125 130

bore for limiting the compression of the body due to weight supported by the caster.

7. A sliding caster, comprising a substantially conical resilient body wider at its base than at its top and having an axial bore molded wider at its top than at its bottom; a pintle having an enlarged ball head centered adjacent the lower end of the bore and adapted for universal rocking motion with

10 respect to the body; and a metallic shell embracing the lower portion of the body and having an axially disposed raised socket portion entering the lower end of the bore and forming a seat for the lower end of the pintle.

15 8. In a sliding caster as set forth in claim 7; said pintle having a collar thereon disposed within the enlarged upper end of the bore for limiting the compression of the body due to weight supported by the caster.

20 9. A sliding caster, comprising a resilient body wider at its base than at its top; and having an axial bore molded wider at its top than at its bottom; a pintle having an enlarged ball head centered in the lower end 25 of the bore, and adapted for universal rocking motion with respect to the body; and a metallic shell embracing the lower portion of the body.

10. In a sliding caster as set forth in claim 30 9; said pintle having a collar thereon disposed within the enlarged upper end of the bore for limiting the compression of the body due to weight supported by the caster.

11. A sliding caster comprising a substantially semiglobular resilient body wider at 35 its base than at its top and having a molded axial bore wider at its top than at its bottom; a pintle having an enlarged globular lower end centered in the lower end of the 40 bore, and adapted for universal rocking motion with respect to the body; said pintle having a collar thereon disposed within the enlarged upper end of the bore; and a metallic shell on the base of the body having 45 an axially disposed raised socket portion entering the lower end of the bore and forming a seat for the lower end of the pintle.

12. A sliding caster comprising a body having a bore, with an enlarged recess at its 50 lower end; a pintle in said bore having an enlarged head disposed within said recess, and a shell mounted around the body having a seat for the pintle entering the lower end of the recess.

13. A sliding caster comprising a body of 55 non-resilient material having a bore with an enlarged recess at its lower end and an enlarged recess at its upper end; a pintle in said bore having an enlarged head disposed within said lower recess and adapted for universal rocking movement with respect to the body; and a shell of slidable material mounted around the body having a seat for the pintle entering the lower end of the lower recess.

14. A sliding caster comprising a resilient body of substantial thickness having a bore extending therethrough with enlarged recesses at its top and bottom; a pintle in said bore adapted to pivot universally of the body having an enlarged head disposed in the bottom recess; and a slidable shell for the body having a raised seat entering the bottom recess for the pintle head.

15. A sliding caster comprising a resilient body of substantial thickness having rounded edges and having a bore extending therethrough with enlarged recesses at its top and bottom; a pintle in said bore adapted to pivot universally of the body having an enlarged head disposed in the bottom recess; and a cup-shaped shell having its edges rolled around the body, said shell having a raised seat entering the bottom recess for the pintle head.
